[57] CLAIM

The ornamental design for the portable phone holster, as shown and described.

DESCRIPTION

FIG. 1 is a front-perspective view of my portable phone holster;

FIG. 2 is a fragmentary, side-elevational view thereof rotated through 180°;

FIG. 3 is a fragmentary, bottom-plan view thereof;

FIG. 4 is a fragmentary, top-plan view thereof;

FIG. 5 is a fragmentary, rear-elevational view thereof;

FIG. 6 is a fragmentary, front-elevational view thereof; and, FIG. 7 is a rear perspective view.

The broken line showing of a portable phone is for illustrative purposes only and forms no part of the claimed design.
